DESIGN FOR A GRILLE GUARD

Gustave F. Bahr, Fairfield, Conn., assignor to Casco Products Corporation, Bridgeport, Conn., a corporation of Connecticut

Application March 21, 1939, Serial No. 83,819

Term of patent 14 years

To all whom it may concern:

Be it known that I, Gustave F. Bahr, a citizen of the United States, residing at Fairfield, in the county of Fairfield and State of Connecticut, have invented a new, original, and ornamental Design for Grille Guards, of which the following is a specification, reference being had to the accompanying drawing, forming part thereof.

Figure 1 is a front elevational view of a grille guard, showing my new design.

Fig. 2 is a side elevational view of the same.

I claim:

The ornamental design for a grille guard, as shown.

GUSTAVE F. BAHR.
